[57] CLAIM

The ornamental design for a vehicle grille, as shown and described.

DESCRIPTION

FIG. 1 is a front perspective view of a vehicle grille embodying my new design, the front of an automotive vehicle being shown fragmentally to show the environment in which the grille is used and not being part of the design; FIG. 2 is a front elevational view thereof; FIG. 3 is a rear elevational view thereof; FIG. 4 is a top plan view thereof; FIG. 5 is a bottom plan view thereof; and, FIG. 6 is a side elevational view, the side opposite being a mirror image of the side shown.
